UNITED STATES PATENT OFFICE.

BICKNELL HALL, OF ABINGTON, MASSACHUSETTS, ASSIGNOR TO WILLIAM M. HURLEY,
OF ROCKLAND, MASSACHUSETTS.

EYELET-SETTING MACHINE.

Application filed January 5, 1923. Serial No. 610,913.

This invention relates to shoe manufacture and has particular reference to a machine for setting eyelets which are constructed in accordance with Patent No. 1,109,647, dated September 1, 1914, issued to William M. Hurley.

The eyelet of said patent is a so-called "blind" eyelet and is characterized by having a single tubular body or barrel formed with a laterally extended ear at its upper end which is co-extensive with a portion only of the body and which is arranged to lie over the outer surface of the shoe upper and cooperate with a flange formed on the lower end of the body to grip the upper. Said ear is adapted to be concealed by the shoe lace when the shoe is on the foot, whereby the eyelet is rendered nearly invisible.

The eyelets of a row in a shoe upper are all adapted to be secured in the shoe upper with the ears thereof extended in the same direction, or directed toward the opening in the upper; otherwise the ears may not be in a position to be concealed by the shoe lace.

Considerable difficulty has been experienced in inserting and fastening the above-described eyelets in shoes by the use of the ordinary eyeletting machine and for the reason that the eyelets are delivered to the eyelet-setting tool in promiscuous order; that is, the eyelets will be delivered for insertion in the shoe upper with the ears extended in various haphazard directions, and the eyelets must be turned by hand, or otherwise manipulated to arrange them in such a manner that all eyelets in the upper will be properly inserted with the ears thereof directed toward the opening in the shoe upper.

An object of this invention is to provide an eyeletting machine especially adapted to insert and set the above described type of eyelet, and having means to arrange the eyelets in position for setting with the ears thereof all directed in the same direction.

In carrying out this object of the invention, I may provide an eyeletting machine of a more or less common type with means acting upon the eyelets in their passage from the eyelet-hopper to the setting-tool, to arrange in an orderly manner eyelets which are discharged in a haphazard manner from said hopper; and said means may comprise

an inclined race-way extended from the hopper to the setting tool and having means, which may be assisted by gravity, to arrange the eyelets with the ears thereof directed in the same direction.

A further object is generally to improve the construction and operation of eyelet-setting machines.

Fig. 1 is a side elevation of an eyelet-setting machine embodying my invention.

Fig. 2 is a plan view of the machine of Fig. 1.

Fig. 3 is a partial sectional plan view of an eyelet-hopper and race-way embodying the invention.

Fig. 4 is a sectional detail of the race-way illustrating the manner in which the eyelets are caused to be re-arranged with the ears thereof directed all in the same direction.

Fig. 5 is an enlarged sectional detail of a portion of the race-way and illustrating more clearly the action of the race-way on the eyelets.

Fig. 6 is a section along line 6—6 of Fig. 3.

Fig. 7 is a section along line 7—7 of Fig. 3.

Fig. 8 is a plan view of the lower eyelet-setting tool.

Fig. 9 is a section along line 9—9 of Fig. 8.

Fig. 10 is a perspective view of the eyelet.

Fig. 11 is a perspective detail illustrating the manner in which the eyelets are set in the shoe upper.

Fig. 12 is a section along line 12—12 of Fig. 1.

Fig. 13 is a sectional detail along line 13—13 of Fig. 3 and illustrating more particularly a preferred construction of an eyelet passage through the wall of the eyelet hopper or kettle.

I have here shown my invention applied to a simple form of eyelet-setting machine, although it may be applied to other types of machines. The eyelet-setting machine here shown, comprises a frame 15 formed or provided with an upper arm 16 in which an upper eyelet-setting tool 17 is adapted to be held removably, and a lower arm 18 in which the plunger 19 is reciprocably supported; and said plunger may comprise the lower eyelet-setting tool. Said plunger is or may be reciprocated by suitable means as

the lever 20, which latter may be pivoted on the pin 21 carried by the frame 15. The rear end of said lever may be pivoted to a connecting rod 22 and said connecting rod 5 may be pivoted to a disc 23, which latter is or may be fixed to the end of an operating shaft 24 journalled in the frame 18. It is apparent that, as said shaft is rotated, the lever 20 is reciprocated to move said plunger 10 19 toward and away from said upper setting tool.

Said shaft 24 may be rotated by power means including the continuously rotating wheel 25, which latter is mounted for rotation 15 on said shaft 24. A clutch is or may be provided to connect said wheel and shaft, whereby to rotate the shaft. Said clutch may comprise a U-shaped frame 27 the arms 28 of which are disposed about the hub 29 fixed to said shaft 24; and said arms are pivoted to said hub. A spring 30 may serve to bias said frame 27 into driving engagement with the clutch teeth 31 of said wheel 25 and said frame may be restrained from such clutching engagement by a cam lever 32, which latter may be controlled by a foot pedal, not shown. Said lever 32 may be so disposed that it serves, when the foot-pedal is released, to move said clutch frame 27 out of driving engagement with the wheel 25 whereby movement of the plunger 19 may be arrested about at the bottom of its stroke.

A slide 35 is disposed to the rear of the eyelet setting tools and on the horizontal face 36 of the frame 15. Said slide is or may be formed or provided with two depending and spaced projections 37 between which the upper end of an operating arm 38 is or may be removed; and said arm is or may be integral with the reciprocating lever 20, whereby the slide and the plunger 19 may operate in unison.

Said slide 35 is or may be formed with a downwardly inclined top face 39 which is adapted to support the eyelet raceway 40 and hopper 41, which latter may be disposed at the upper end of the race-way. Said hopper is preferably cylindrical in cross-section and of suitable dimensions to contain a substantial supply of eyelets, which may be contained therein in promiscuous or haphazard order. A cover 42 may be provided whereby to prevent accidental escape of eyelets; and the cover may be removed or rotated to uncover the hopper whereby to admit of the introduction of eyelets into the hopper.

The hopper and race-way may be integral, as here shown, or may be otherwise constructed and arranged.

A circular brush 43 is rotatably disposed within the hopper and is adapted to be reciprocated at each stroke of the supporting slide 35 whereby to brush eyelets out of the hopper into the race-way. Said brush is or

may be secured to a shaft 44 which is journalled in the hopper-base and extends therebelow. A crank arm 45 is or may be fixed to the lower end of said shaft and a link 46 may be pivotally connected with said crank-arm and the frame 15 of the machine. With this arrangement, the shaft 44 and brush are reciprocated at each stroke of the hopper.

A portion of the lateral circular wall is or 75 may be formed or provided with passages 48 therethrough which communicate with a passage 49, which latter extends to the upper end of the race-way; and the reciprocating brush serves to brush or sweep the eyelets, one at a time, through said passages 48 and into the passage 49, from which passage said eyelets may descend, by gravity, assisted by the jar and vibration of the machine, 80 into the race-way 40.

The inclined race-way 40 is provided with a groove 50 which is in communication at its upper end, with the passage 49, and the eyelets are adapted to pass, by gravity, down said inclined groove 50 to the lower end of 90 the race-way, for delivery to the eyelet-setting tools.

The above construction is or may be more or less common, in principle, with eyelet-setting machines.

As illustrated in Fig. 10, the type of eyelet adapted to be used in connection with this invention is formed with the tubular body 55 from the upper end of which is laterally extended the ear 56, which ear is co-extensive with a portion only of said body. Said eyelets are adapted to be inserted and secured in a shoe upper 57 in the manner illustrated in Fig. 11, with the ears of the eyelets of the row all directed toward the opening-edge 58 of the upper, whereby said ears are in position to be concealed under the lace 59 passed through the eyelets. A flange 60 is or may be formed by upsetting the lower edge of the eyelet, and the upper is adapted to be retained between said flange 60 and the ear 56 of the eyelet.

Preferably the body-portion of the eyelet is of greater diameter than the height thereof, and the eyelet passages 48 in the hopper or kettle have corresponding dimensions, that is, the width of the slots are greater than the heights thereof. With this arrangement, only eyelets that are upright in the hopper, or resting with the ears thereof in contact with the bottom wall of the hopper, are brushed through said passages 48, and eyelets which are disposed on their sides will not fit the passages and, consequently, will not pass therethrough. The bottom portions of said passages 48 preferably are relieved or formed with oppositely-disposed slots 48a through which the ears of the eyelets may pass as the body-portions of the eyelets pass through the passages 48.

The eyelets above described are discharged from the hopper 41 into the upper end of the race-way 40 in a promiscuous order so that, with the usual form of race-way, some eyelets would be delivered with the ears 56 foremost, and others, with the ears rearmost. As thus delivered, it is difficult to manipulate the eyelets, at the eyelet setting tools, and the shoe upper, in such a way as to cause the eyelets to be set in the upper with the ears thereof all properly directed. This invention provides means to re-arrange the necessary eyelets, and preferably as they pass downward in the race-way, whereby all eyelets will be delivered to the setting tools with the ears thereof all directed in the same direction, as rearwardly.

As illustrated in Fig. 4, some eyelets *a* may be delivered into the race-way in proper order while other eyelets *b* may be delivered in the reverse order, and it is desirable to reverse relative position of said eyelets *b* before they are finally secured in the shoe upper.

The race-way itself may be constructed and arranged to effect the reversal of the necessary eyelets so that all eyelets may have the ears thereof properly directed. To this end, the groove 50 in the race-way, which lies, in the main, in the top part of the race-way, and is adapted to support the eyelets in an upright position, is brought around to the side of the race-way, more or less gradually, as indicated at 50^a, and then brought back to the top of the race-way. This arrangement of groove may be made in any suitable or desirable manner, as by cutting the groove directly in the desired form, or by forming a straight groove, and then twisting a portion of the race-way at right angles to the remaining portion thereof whereby to form the side groove 50^a. This arrangement provides a side loop in the groove in which the eyelets are supported horizontally and in which the reversing action of the eyelets is effected. Preferably the inclination of the race is such that all portions of the groove, including the loop-portion 50^a, are inclined downwardly, so that the eyelets will move freely down the groove. The bottom wall of the loop 50^a is relieved or cut away, as by forming the slot 65 therein, beneath the path of travel of the ears of the eyelets; and said slot is adapted to receive the ears of the eyelets. The top and bottom edges 66 and 66^a, respectively, are shaped to provide cam surfaces which serve gradually to rotate the eyelets into the required position as they pass downwardly into the race-way.

The action of the race-way as thus described is substantially as follows:

As the machine is operated and the race-way and hopper are moved back and forth, the brush 43 is reciprocated in the hopper,

and eyelets are brushed out of the hopper into the race-way groove 50, wherein they will be supported in upright position with the ears thereof resting upon the bottom of the groove; but some of the ears of the eyelets may be directed up and others down the groove. The eyelets are adapted to be a loose fit in the groove so that they may slide freely down the groove, yet a sufficiently close fit is provided to prevent the binding or wedging of the eyelets in the groove.

As the eyelets descend into the loop-portion 50^a of the groove 50 they are gradually turned over on the sides thereof as illustrated in Figs. 4 and 5 until the eyelets are supported with the bodies thereof disposed approximately horizontal. As the eyelets pass down the loop portion horizontally, they pass over the slot 65 in the lower wall of the loop. Since the ears of the eyelets extend laterally of the eyelet on one side only, the eyelet is overbalanced on that side and consequently the weight of the ear, which may be assisted by the tendency of the eyelet to roll down the loop, causes the eyelets to roll into such a position that the ears depend approximately vertically into the slot. Each eyelet, as it passes over the slot in the loop is caused to rotate in a clockwise or counter clockwise direction, depending upon whether or not the ear of the eyelet heads or trails into the loop, until the ear hangs lowermost in the slot.

Fig. 5 illustrates in detail and by successive steps, the rotating action of the eyelet (right hand side) as it passes into the slotted position of the loop.

As the eyelet passes down the loop with the ear thereof depending, said depending ear is brought into contact with the lower edge 66^a of the slot 65. Said edge tends to prevent further downward movement of the eyelet but as the groove 50 is unrestricted the body portion of the eyelet is free to pass on and said edge 66^a serves to rotate the eyelet in a counter-clockwise direction, until finally, the eyelet is rotated to such a position that the ear thereof is directed up the groove 50, or trails the body of the eyelet. The edge 66 of said slot 65 is given a suitable cam shape to act successfully on the eyelets. The eyelet, as thus arranged, then passes into the portion of the groove 50 and in passing therein, is restored to its initial upright position and passes downwardly to a delivery position at the lower end of the race-way.

With this arrangement, it will be seen that regardless of the initial promiscuous disposition of the eyelets as they are discharged from the hopper, all eyelets will be finally delivered with the ears thereof extended in the same direction.

In connection with the above-described

eyelet, I prefer to employ a special eyelet-setting tool, so arranged as to hold the eyelet in the proper position until it is finally set in the shoe upper. To this end, the 5 plunger 19 may be provided with the usual spring-pressed center pin 70, which is adapted to enter the tubular passage in the eyelet body, whereby to retain the eyelet centrally located during the setting operation. 10 In addition, the plunger is or may be formed with a transverse recess 71 disposed in the top face of the plunger between the pin 70 and the delivery end of the race-way; and a recess 72 may extend downwardly in 15 said plunger from the bottom of said recess 71. A guide member 73 is received in said recess 71; and said guide member may have the two upstanding and spaced projections 74 between which the ear of the eyelet is received, whereby, in cooperation with the pin 70, the eyelet will be held on the tool without angular movement. Said guide member may also have a depending projection 75 which is adapted slidably to be received in 20 the recess 72, and a spring 76 may be disposed in said recess 72 beneath said projection 75, whereby to support said guide member yieldingly in elevated position. When the plunger 19 is moved upwardly, 25 said guide member will engage the shoe upper and be depressed thereby to permit the eyelet to be inserted and set in the shoe upper.

The invention may be otherwise modified 30 without departing from the spirit thereof.

I claim:—

1. An eyelet feeding mechanism for eyelet-setting machines adapted to set single barreled eyelets provided with ears extended 40 laterally from and co-extensive with portions only of the eyelets, comprising a hopper arranged to contain a supply of promiscuously arranged eyelets, and means to re-arrange the promiscuously arranged eyelets and to

45 present the re-arranged eyelets to the eyelet-setting means with the ears of all the eyelets lowermost and all ears arranged on the same sides of the barrels and in a predetermined angular relation with the setting means.

50 2. An eyelet feeding mechanism for eyelet-setting machines adapted to set eyelets provided with ears extended laterally from and co-extensive with portions only of the eyelets, a hopper adapted to contain a supply of promiscuously arranged eyelets, and means including a raceway to conduct the eyelets from said hopper to the eyelet-setting machine and to rotate the eyelets about their own axes into a delivery position in which 55 the ears thereof are directed in the same relative direction.

60 3. An eyelet feeding mechanism for eyelet setting machines adapted to set eyelets provided with ears extended laterally from and co-extensive with portions only of the

eyelets comprising a hopper from which the eyelets may issue in promiscuous order, and means to effect the transfer of eyelets from said hopper to the setting means with the ears lowermost and the rotation of said eyelets about their own axes into a predetermined orderly position with the ears all behind the bodies of the eyelets for delivery to said eyelet-setting means in such position.

70 4. An eyelet feeding mechanism for eyelet setting machines adapted to set eyelets provided with ears extended laterally from and co-extensive with portions only of the eyelets comprising a hopper arranged to contain a supply of promiscuously arranged eyelets, and a race-way adapted to conduct eyelets from said hopper to the setting means, said hopper being arranged to deliver eyelets in upright position with the ears of said eyelets arranged in promiscuous 80 angular relation, and said raceway having means associated with it to re-arrange said eyelets with the ears thereof disposed all in the same predetermined order for delivery 85 to the setting means.

90 5. An eyelet feeding mechanism for eyelet setting machines adapted to set eyelets provided with ears extended laterally from and co-extensive with portions only of the eyelets comprising a hopper arranged to 95 contain a supply of promiscuously-arranged eyelets, and a race-way adapted to conduct eyelets from said hopper to the setting means, said hopper being arranged to deliver eyelets in upright position with the ears of said eyelets arranged in promiscuous 100 angular relation, and said race-way having means associated with for effecting the rotation of said eyelets into positions wherein the ears thereof are disposed in the same predetermined order for delivery to the setting means.

105 6. An eyelet feeding mechanism for eyelet setting machines adapted to set eyelets provided with ears extended laterally from and co-extensive with portions only of the eyelets comprising a hopper arranged to contain eyelets in promiscuous arrangement, means to effect the transfer of eyelets from said hopper to the setting means including means to arrange the eyelets in upright position with the ears bottommost, and means to receive said upright eyelets and to rotate them about their own axes into a second orderly plan with the ears all behind the bodies of the eyelets and deliver said eyelets 110 as last re-arranged to the setting means.

115 7. An eyelet feeding mechanism for eyelet setting machines adapted to set eyelets provided with ears extended laterally from and co-extensive with portions only of the eyelets, comprising a hopper arranged to contain a supply of promiscuously-arranged eyelets, and a race-way adapted to 120 conduct eyelets from said hopper to the eye- 125

let-setting means, said hopper arranged to deliver eyelets in upright position with the ears of the eyelets arranged in promiscuous angular relation, and said raceway having means associated with it to incline said eyelets from an upright position and to effect the rotation of said eyelets into an orderly position with the ears thereof extended all in the same direction, and deliver said eyelets to the setting means.

8. An eyelet feeding mechanism for eyelet setting machines adapted to set eyelets provided with ears extended laterally from and co-extensive with portions only of the eyelets, comprising a hopper arranged to contain a supply of promiscuously arranged eyelets, and a race-way adapted to conduct eyelets from said hopper to the setting means, said hopper arranged to deliver eyelets in upright position with the ears of said eyelets arranged in promiscuous angular relation, and said race-way having means associated with it to incline said eyelets from an upright position and to effect the rotation of said eyelets into an orderly position with the ears thereof extended all in the same direction, and means to receive said eyelets as thus arranged and restore them to an upright position and re-arrange the eyelets in an orderly position with the ears thereof extended all in the same direction and deliver said eyelets as last re-arranged to the setting means.

9. An eyelet feeding mechanism for eyelet setting machines adapted to set eyelets provided with ears extended laterally from and co-extensive with portions only of the eyelets, comprising a hopper adapted to contain a supply of promiscuously-arranged eyelets, and a race-way adapted to conduct eyelets between said hopper and eyelet-setting means, said race-way having means, assisted by gravity, to effect the re-arrangement of the eyelets passing therein from a promiscuous order to a predetermined order wherein the ears of the eyelets extend in the same direction and deliver the eyelets in such predetermined order to said eyelet-setting means.

10. An eyelet feeding mechanism for eyelet setting machines adapted to set eyelets provided with ears extended laterally from and co-extensive with portions only of the eyelets comprising a hopper adapted to contain a supply of promiscuously-arranged eyelets, and a race-way extended between said hopper and eyelet-setting means having a guide groove for the eyelets arranged to hold the eyelets in a horizontal position and effect the rotation of said eyelets into a position wherein the ears thereof depend downward, and having means arranged subsequently to rotate said eyelets into another position wherein the ears thereof extend behind the bodies of the eyelets in the groove.

11. An eyelet feeding mechanism for eyelet setting machines adapted to set eyelets provided with ears extended laterally from and co-extensive with portions only of the eyelets, comprising a hopper adapted to contain a supply of promiscuously-arranged eyelets, and means to effect the rotation of said eyelets about their own axes into a position wherein the ears are extended in the same direction between said hopper and eyelet-setting means.

12. An eyelet feeding mechanism for eyelet setting machines adapted to set eyelets provided with ears extended laterally from and co-extensive with portions only of the eyelets, comprising a hopper adapted to deliver eyelets in promiscuous order and means to receive and re-arrange said eyelets into an orderly plan comprising means to support said eyelet horizontally and means to effect the rotation of said eyelets into a position wherein the ears of said eyelets are all depending substantially vertically.

13. An eyelet feeding mechanism for eyelet setting machines adapted to set eyelets provided with ears extended laterally from and co-extensive with portions only of the eyelets, comprising a hopper adapted to contain a supply of promiscuously-arranged eyelets, and means to receive said eyelets in promiscuous order from said hopper and deliver them in predetermined arrangement to said eyelet-setting machine, comprising a race-way having an eyelet-guide groove adapted freely to support said eyelet substantially horizontally, said groove having a relieved portion disposed beneath the path of movement of the ears of the eyelets into which the ears are adapted to drop.

14. An eyelet feeding mechanism for eyelet setting machines adapted to set eyelets provided with ears extended laterally from and co-extensive with portions only of the eyelets, comprising a hopper adapted to contain a supply of promiscuously-arranged eyelets, and means to receive said eyelets in promiscuous order from said hopper and deliver them in predetermined arrangement to the setting means comprising a race-way provided with an eyelet-guide groove having an upper portion adapted to receive the eyelets in upright position with the ears thereof directed promiscuously behind and also in front of the eyelets, an intermediate portion adapted freely to support the eyelets horizontally and said intermediate portion having a relieved portion disposed beneath the path of travel of the ears of said eyelets into which the ears are adapted to fall, a lower portion adapted to support the eyelets in upright position, and means to rotate the eyelets as they pass into the lower portion of the

guide groove into a position wherein the ears thereof are all disposed behind the bodies of the eyelets.

15. An eyelet feeding mechanism for eyelets setting machines adapted to set eyelets provided with ears extended laterally from and co-extensive with portions only of the eyelets, comprising a hopper adapted to contain a supply of promiscuously-arranged eyelets, an inclined race-way having an eyelet-guide groove formed with an upper portion adapted to receive the eyelets in upright order from the hopper with the ears thereof directed promiscuously in front of and behind the bodies of the eyelets, and a lower portion adapted to support the eyelets in upright order with the ears thereof all disposed behind the bodies of the eyelets, and an intermediate portion having means to rearrange the eyelets from one to the other position.

16. An eyelet feeding mechanism for eyelet setting machines adapted to set eyelets provided with ears extended laterally from and co-extensive with portions only of the eyelets, comprising a hopper adapted to contain a supply of promiscuously-arranged eyelets, an inclined race-way having an eyelet-guide groove formed with an upper portion adapted to receive the eyelets in upright order from the hopper with the ears thereof directed promiscuously in front of and behind the bodies of the eyelets, and a

lower portion adapted to support the eyelets in upright order with the ears thereof all disposed behind the bodies of the eyelets, and an intermediate portion arranged freely to support the eyelets horizontally, said intermediate portion having a relieved portion disposed beneath the path of movement of the ears of said eyelets into which said ears are adapted to fall, and means to rotate said eyelets all in the same direction as they pass into the lower portion of the guide groove and into a position where the ears are all disposed behind the eyelets.

17. A raceway for eyelet feeding mechanisms of eyelet-setting machines adapted to set eyelets provided with ears extended laterally therefrom, said race-way having a channel through which the eyelets pass, said channel having an intermediate portion constructed and arranged to effect the rotation of the eyelets by gravity about their own axes into a predetermined position wherein the ears of the eyelets are disposed all in the same relation as they pass along the channel, and said channel having a delivery portion constructed and arranged to receive the rotated eyelets and to guide them for movement along the raceway and to hold them against further rotation.

In testimony whereof, I have signed my name to this specification.

BICKNELL HALL.
